UNITED STATES PATENT OFFICE.

CAMDEN MEARS AND JOHN W. MEARS, OF BLOOMSBURG, PENNSYLVANIA.

WASHING-MACHINE.

SPECIFICATION forming part of Letters Patent No. 380,445, dated April 3, 1888.

Application filed November 11, 1886. Serial No. 218,609. (No model.)

To all whom it may concern:

Be it known that we, CAMDEN MEARS and JOHN W. MEARS, citizens of the United States, residing at Bloomsburg, in the county 5 of Columbia and State of Pennsylvania, have invented a new and useful Improvement in Washing-Machines, of which the following is a specification.

Our invention relates to improvements in 10 washing-machines; and it consists in the peculiar combination of devices and novel construction and arrangement of the various parts for service, substantially as hereinafter fully described, and particularly pointed out in the 15 claims.

The primary object of our invention is to provide an improved washing machine which can be operated with great ease, and which shall thoroughly and effectively cleanse the 20 fabrics placed therein of all dirt within a very short space of time.

In the accompanying drawings, which illustrate an improved washing-machine embodying our invention, Figure 1 is a perspective view. Fig. 2 is a vertical longitudinal sectional view on the line $z z$ of Fig. 5, showing the folding tub-support folded against one end of the suds box or receptacle. Fig. 3 is a vertical transverse sectional view on the line $x x$ of 25 Fig. 5. Fig. 4 is an end elevation showing the tub-support folded against one end of the suds-box. Fig. 5 is a horizontal sectional view on the line $y y$ of Fig. 2. Figs. 6 and 7 are detached detail views of parts of our improvements. Fig. 8 is a side elevation showing the cover turned to a vertical position and the rubber thrown back out of the way to permit the fabrics to be removed and passed through a wringer. Fig. 9 is a top plan view 30 of a modification showing the device as adapted to be operated by two persons from both ends.

Referring to the drawings, in which like letters of reference denote corresponding parts in 35 all the figures, a designates the suds box or receptacle of our improved washing-machine, which comprises the vertical side walls, a , the vertical end walls a' , which are arranged at right angles to the side walls, a horizontal bottom, a^2 , and a hinged cover or lid, a^3 . The side walls, a , of the said receptacle are provided on their inner opposing surfaces near

their ends with vertical grooves a^5 , in which are fitted the extremities of the end walls, a' , and to the said side and end walls is secured 55 the horizontal bottom of the receptacle, suitable tension-rods, a^6 , being passed through the sides to draw the several walls of the receptacle together, and thereby provide a very rigid and firm structure which shall not be liable to 60 leak, and can be manufactured very rapidly and cheaply.

The cover or lid a^3 of the suds-box is permanently connected at one edge to the upper edge of one of the end walls thereof by means of 65 strap-hinges a^4 , the joint of which is arranged within the line of juncture of the inner edge of the said vertical wall and the lid, so that when the latter is turned to an upright or vertical position—as, for instance, when the 70 wringer presently described is in use or it is desired to remove the contents of the receptacle—the water that may adhere will escape down on the cleat or the under side thereof, and thence into the suds-box, as will 75 be very readily understood.

The suds-box is made substantially rectangular in form, and it is supported at a suitable height above the ground by means of vertical standards or legs A' , which are arranged 80 near the corners of the suds-box and rigidly affixed thereto by the same through-bolts or tension-rods a^6 which connect the several walls of the suds-box together.

The suds-box is provided with a horizontal 85 flange or ledge, b , on its inner side and at the upper portion thereof, on which rests the hinged cover or lid of the receptacle when in a closed position, and a series of vertical ribs, B , are also arranged within the suds-box and 90 rigidly affixed at their upper and lower ends in the said horizontal ledge and the bottom of the box, respectively, as shown. These vertical ribs B are arranged in a circle in the suds-box, as clearly shown in Fig. 5 of the drawings, so that the fabrics or clothing in the box are prevented from accumulating in the angular corners of the rectangular box, and the 95 said ribs are made substantially hexagonal or other angular form in cross-section. A series 100 of horizontal radial ribs are rigidly affixed to the bottom of the suds-box, as at B' , and the upper faces of these horizontal ribs are made angular in cross-section. These vertical and

horizontal ribs serve to exert a rubbing action on the fabrics in the receptacle, which are caused to partake of a whirling motion by the action thereon of an oscillating agitator or 5 rubber operating therein, the said fabrics impinging violently against the angular faces of the fixed ribs.

C designates the oscillating agitator or rubber which is located in the suds-box, and it is 10 arranged in a horizontal position and normally rests upon or is elevated slightly above the horizontal ribs B' of the bottom. This agitator or rubber is shown in detail in Fig. 6 of the drawings, and it comprises a horizontal disk, c, and a series of depending fixed ribs, c' c'', which are arranged radially of the disk and on the lower or under side thereof. 15 There are preferably eight of these radial ribs provided, although the number thereof can 20 be varied without departing from the spirit of our invention, and four of these eight ribs meet at the center of the disk c, while the other four terminate a short distance from the said center to leave intermediate spaces, as 25 shown. These ribs are arranged out of contact with each other at their side edges to leave intermediate spaces for the free circulation of water therein, and each of the radial ribs is provided at its outer terminal ends with integral depending enlargements c'', which are 30 rounded, preferably, so that they will not tear or otherwise injure the fabrics and still serve to more readily catch the same during the oscillating motions of the rubber and thus serve 35 to more effectively and thoroughly agitate the fabrics in the water. This agitator or rubber is carried and actuated by a vertical standard, C', which is substantially square in cross-section and provided at its lower end with integral lugs or feet C'', through which are passed 40 bolts that serve to rigidly affix the horizontal disk of the agitator to the standard C' thereof. D designates the journal-plates in which the driving mechanism for the oscillating agitator 45 or rubber is supported, the peculiar construction of which I will now proceed to describe. The plates are arranged in a horizontal position one above the other, and the plate D is arranged beneath the plate E. I will there- 50 fore term the plate D as the "lower" and the other plate as the "upper" plate. The lower plate, D, is provided on its upper side with vertical flanges or ribs d, which are cast or formed integral therewith, and the upper plate 55 is provided with recesses or grooves e on its under side, into which the upper edges of the integral flanges or ribs are fitted to prevent displacement of the horizontal journal-plates with relation to each other, the said plates 60 having vertical aligned openings f, through which are passed bolts f', which also pass through the lid or cover, and thus secure the said plates to each other and to the cover of the suds-box. These journal-plates are ar- 65 ranged at or near the center of the hinged cover, and they have transverse openings D', around which are formed concentric integral

bosses D'', which form the bearings for the hubs of a master-gear which constitutes a portion of the driving mechanism for the oscillating 70 agitator or rubber. These central openings and bosses are arranged in line with each other and with a central opening in the hinged cover of the receptacle, and through the opening in the cover and a central opening in the hub of 75 the master-gear passes the upper extremity of the square standard or shaft C' of the oscillating rubber, as will be more fully described hereinafter.

The lower plate, D, is provided near one of 80 its side edges with a longitudinal groove in its upper side, as at d', and the upper plate is provided with a groove, e', in its lower side, which is arranged in line with the corresponding groove in the upper plate. These grooves 85 are preferably formed by right-angled parallel flanges that are formed integral with the plates; but they may be made by cutting into the plates, as is obvious.

G designates the master gear-wheel, which 90 is provided with an integral hub, g, which projects laterally from the side faces of the wheel. This hub is journaled in the aligned bosses of the bearing-plates, so as to be free to rotate therein, and it has a central square opening, g', therein, through which passes the upper end of the square standard C' of the agitator or rubber, this upper end of the standard having a transverse opening, g'', through which passes a key or pin, G', that serves to 95 connect the agitator-standard with the master gear-wheel, so that the shaft or standard is rotated or oscillated with the wheel, as is obvious. The master-gear is actuated by a reciprocating rack, H, which works in the aligned guide-grooves formed in the journal or bearing plates. This rack is provided with a back plate, on which the teeth are formed, and the edges of the back plate are extended beyond the terminal ends of the teeth, so that the plate can move freely in the aligned 100 grooves in the bearing-plates and thus cause the rack to run or reciprocate in a true line. The teeth on the reciprocating rack are formed in the inner side of the back plate thereof, so 105 that the rack will actuate the master-gear properly, and the rack is further provided with a pin, h, which is formed integral therewith and located on the outer side of the rack, the said 110 pin being arranged at right angles to the back plate and extending beyond the edges of the bearing-plates, so that the inner end of a link or pitman, i, can be readily connected therewith to actuate the same. The rack is reciprocated by means of a vertically-disposed 115 hand-lever, I, which is arranged at one end of the machine, and this lever is pivoted at an intermediate point of its length to the suds-box, as will be presently described, and has the outer end of the link or pitman i connected 120 thereto, so that the movements of the lever will be communicated to the rack to likewise 125 actuate the same.

J designates a casting, which is provided

with short arms *j*, which project from opposite sides of the body of the same, and the outer ends of these short arms are formed into trunnions *j'*, which are journaled in aligned 5 openings or bearings *k*, which are formed in the outer ends of suitable brackets, *K*, which are rigidly affixed to one of the end walls of the suds-box. These brackets are each formed in a single piece of metal, and they each comprise 10 the diverging arms *k'*, which are provided at their inner ends with right-angled perforated lugs, through which are passed screws that serve to secure the brackets to the suds-box. The brackets are arranged in a vertical 15 position a short distance from and parallel with each other, and the bearings or openings *k* are formed in their outer ends and at the point where the diverging arms join each other. The casting *J* is rigidly affixed or secured 20 to the hand-lever *I* at an intermediate point of the length thereof, and the trunnions of the said casting are fitted and journaled in the aligned openings or bearings in the brackets *K*, thereby pivotally supporting the hand-lever upon one of the end walls of the suds-box. The lower end of the lever is adapted 25 to impinge against the lower edge of the suds-box, and it has a buffer, *I'*, of any suitable resilient material—as, for instance, rubber or leather—rigidly affixed thereto, so that the impact or force of the lever upon the suds-box when it strikes the same will be very materially deadened or decreased.

One end of the pitman *i* is bent or formed 30 into an eye, through which the pin on the reciprocating rack is passed, the pitman being held on the pin by a key, as shown, while the opposite end of the pitman is bent at right angles to the longitudinal axis thereof, and threaded, the said threaded end being passed 35 through a suitable opening in the lever, and connected thereto by a suitable nut, which screws upon the threaded portion of the same.

L designates a fixed stop, which is secured 40 upon the upper side of the hinged lid or cover of the suds-box and at the free edge thereof, and this stop is arranged in the path of the pin of the reciprocating slide and the inner end of the pitman, so that when the lid or cover is 45 raised to an elevated position the pin will impinge against the stop, and thereby prevent the cover from further rearward movement, which is very desirable in wringing the fabrics, as the cover is then supported in place 50 without requiring any attention on the part of the operator.

An elastic cushion, *m*, is fitted around the upper end of the standard or shaft *C* of the oscillating rubber, and this cushion is interposed 55 between the key of the shaft and the upper bearing-plate, as shown. This cushion may be made of a piece of rubber, leather, or other suitable material of a like nature, or a coiled spring can be used, if desired.

60 The end of the suds-box opposite to the end where the hand-lever is connected thereto is provided with an inclined discharge-board, *M*,

which is arranged at the upper edge of the end wall of the suds-box, and to the outer edge of the inclined discharge-board is secured or affixed a vertical flange or wall, *M'*, upon which a wringing-machine of any approved or desired pattern is adapted to be secured, as will be very readily understood. Short side walls, *M*, are rigidly affixed to the ends of the inclined 70 and vertical walls *M M'*, and serve to prevent the water that falls upon the discharge-board from the wringer, when the latter is in use, from escaping at the sides of the suds-box. 75

The inclined discharge-board is extended beyond the end wall to which it is affixed, as shown, and the side walls of the suds-box are also extended, to form a recess between the side and end walls, in which the folding tub-support or wash-bench *N* is adapted to be folded very compactly and snugly. This tub-support consists of two sections which are hinged together at their contiguous ends, as at *n*, and the folding legs *N'*, which are pivoted 80 to the outer ends of the outer section of the said tub-support. The sections of the tub-support are each made of two parallel side bars and two or more connecting-bars, which are firmly united or connected together for strength 85 and durability, and the folding legs at the outer end of the support are connected by a transverse bar, so that the legs mutually brace one another and move simultaneously. The inner section of the tub-support is hinged 90 to the lower edge of one of the end walls of the suds-box, and the outer section of the said support has the upper ends of the folding legs pivoted thereto. The hinged sections of the tub-support are adapted to fold 95 against one another and the end of the suds-box, to which the inner section is connected, and the folding legs are adapted to fold against the outer section of the tub support, thereby compactly and snugly folding the entire parts 100 of the said tub-support together. The said tub-support is housed partly within the recess at one end of the suds-box, and it is held in its folded position by means of a suitable locking device, *n'*, which preferably consists of a 105 hook which is pivoted to the receptacle, and an eye which is secured to the pivoted folding legs of the support.

The operation of our invention will be very readily understood from the foregoing description, taken in connection with the accompanying drawings.

The fabrics and a suitable supply of water are first placed in the suds-box and the upper end of the hand-lever grasped to operate the 115 machine. The movements of the swinging hand-lever are transmitted through the intermediate pitman to the reciprocating rack, which in turn actuates the master-gear, and thus oscillates the standard or shaft *C* and the 120 agitator or rubber. The rubber serves to agitate the water and fabrics in the suds-box, and the enlargements on the ribs thereof catch the fabrics and agitate the same to effect the 125 130

cleansing thereof within a very short time. The continued oscillation of the rubber causes a violent agitation in the water and fabrics of the suds-box, and the fabrics are caused to 5 impinge upon the ribs therein, the combined action of the surging agitating water in the receptacle and the ribs thereof serving to rapidly and effectively cleanse the fabrics from dirt and impurities. When it is desired to 10 use the wringer, the folding tub-support is extended and the legs thereof dropped down to rest upon the floor, and thus support the tub-support in a horizontal position. The wringing-machine is applied to the vertical wall M'; 15 or it can be permitted to remain thereon permanently, as the operation of the machine will not be interfered with by the same, and the hinged lid or cover is thrown back to an upright position until the fixed pin on the rack 20 and the front end of the pitman impinges upon the fixed stop on the lid, thereby preventing the further retrograde movement of the lid, the movement of the hand-lever being limited by the buffer at its lower end coming in contact with the lower edge of the suds-box. The 25 agitator or rubber is now pressed or forced through the hinged lid or cover, so that it will be out of the way of the attendant in reaching for the fabrics, in order to pass them through the wringer, this movement of the agitator being readily performed, as it is not connected with the driving mechanism and passes freely 30 through the square opening in the master-gear.

The water can be readily discharged from 35 the suds-box after the washing and wringing operations have been completed through an outlet-opening, o, formed in the lower corner of one of the side walls of the suds-box, and the water is directed into a suitable receptacle by 40 a short nozzle, o', which is rigidly affixed to the suds-box and either partially or wholly surrounds the outlet-opening therein, as clearly shown in Fig. 1.

The machine is provided with suitable handles, p, so that it can be readily moved or carried, and the cover is likewise provided with a similar handle at its free edge, so that it can be raised.

We do not desire to limit ourselves to the 50 exact details of construction and form and proportion of parts herein shown and described as an embodiment of our invention, as we are aware that changes therein can be made without departing from the principle or sacrificing 55 the advantages thereof.

In large machines it is necessary to provide two hand-levers, which are located at opposite ends of the machine, and connected by intermediate links with two reciprocating rack-bars, which are arranged on opposite sides of the master-gear to alternately rotate the same. The levers are operated alternately by two persons, and the racks are guided in suitable grooves formed in the bearing-plates, as will 60 be very readily understood. In lieu, however, of a lever, we may employ a crank for reciprocating the rack-bar, and an unusual power of

any preferred form may also be connected with the rack or racks to operate the same.

Having thus fully described our invention, 70 what we claim as new, and desire to secure by Letters Patent, is—

1. In a washing-machine, the tub and cover provided with a plate on the cover and a second plate secured to the said first plate, the two being separated by suitable projections, which also support the second plate at both ends, a cog-wheel having an angular hole through it, loosely journaled between the plates, in combination with a vertically-reciprocating angular shaft, which slides freely through the hole in the cog-wheel and a rubber mounted thereon, and a gearing for rotating said wheel, shaft, and rubber alternately in opposite directions, substantially as and for the purposes specified. 85

2. In a washing-machine, the combination of a suds-box having a swinging lid, the journal-plates affixed to the lid and having the aligned openings, a master-gear journaled in the plates and provided with a square opening which aligns with the openings in the plates, an agitator or rubber fixed to the lower end of a square shaft, which passes through the openings in the plates and master-gear and is free to move longitudinally therein, a rack 90 guided by the plates for operating the master-gear and agitator, and a lever connected by a rod with the rack, whereby when the cover is elevated the agitator can be moved or adjusted in close proximity to the same to permit the 95 ready removal of the fabrics, as and for the 100 purpose set forth.

3. In a washing-machine, the combination of a suds-box having a hinged lid, the bearing-plates connected to the lid, a master-gear 105 journaled in the said plates, the agitator connected by an intermediate shaft with the master-gear, a reciprocating rack for actuating the master-gear and having a fixed pin, a swinging hand-lever, a pitman intermediate 110 of the lever and pin of the rack, and a fixed stop arranged in the path of the pin on the rack and adapted to come in contact therewith when the cover is elevated, substantially 115 as described, for the purpose set forth.

4. In a washing-machine, the combination of a suds-box having a hinged lid or cover, the fixed bearing-plates D E, arranged parallel with each other and one having the flanges or ribs fitting in corresponding grooves in the other plate, the hollow aligned bosses 120 therein, the guide-grooves and the through-bolts, the master-gear journaled in the hollow aligned bosses, the reciprocating rack working in the aligned guide-grooves, the agitator or rubber having the shaft passing through the master-gear, and a hand-lever connected with the rack, substantially as described, for the purpose set forth. 125

5. In a washing-machine, the combination 130 of a suds-box having the swinging lid or cover, the fixed bearing-plates thereon, the master-gear journaled in the said plates and having the central square opening, the agita-

tor or rubber having the square shaft passing through the opening in the master-gear and free to move longitudinally therein, the reciprocating rack, a hand-lever connected to the suds-box at an intermediate point of its length and adapted to impinge against the same at its lower extremity, the pitman intermediate of the lever and the rack, and a fixed stop on the lid or cover and arranged in the path of the inner end of the link, and the pin on the rack to which the link is connected,

substantially as described, for the purpose set forth.

In testimony that we claim the foregoing as our own we have hereto affixed our signatures 15 in presence of two witnesses.

CAMDEN MEARS.
JOHN W. MEARS.
